UNITED STATES PATENT OFFICE.

ARTHUR J. BEACOM, OF OMAHA, NEBRASKA.

DESIGN FOR A RING.

48,483.

Specification for Design.

Patented Feb. 1, 1916.

Application filed November 8, 1915. Serial No. 60,450. Term of patent 7 years.

To all whom it may concern:

Be it known that I, ARTHUR J. BEACOM, a citizen of the United States, residing at Omaha, in the county of Douglas and State of Nebraska, have invented a new, original, and ornamental Design for a Ring, of which the following is a specification, reference being had to the accompanying drawing, forming a part thereof.

Figure 1 is a plan view of the ring illustrating my new design. Fig. 2 is an end

view of the same. Fig. 3 is a side view of the ring.

I claim;

The ornamental design for a ring as shown.

In testimony whereof, I have affixed my signature in presence of two witnesses.

ARTHUR J. BEACOM.

Witnesses:

HIRAM A. STURGES,
ARTHUR H. STURGES.
